H. G. CORDLEY

RECIPROCATING PLUG FAUCET

Filed June 18, 1921

Inventor
H. G. Cordley

Attorney

UNITED STATES PATENT OFFICE.

HENRY G. CORDLEY, OF GLEN RIDGE, NEW JERSEY.

RECIPROCATING-PLUG FAUCET.

Application filed June 18, 1921. Serial No. 478,653.

To all whom it may concern:

Be it known that I, HENRY G. CORDLEY, a citizen of the United States, residing at Glen Ridge, in the county of Essex, State 5 of New Jersey, have invented certain new and useful Improvements in Reciprocating-Plug Faucets, of which the following is a description, reference being had to the accompanying drawings, forming a part 10 hereof.

My invention relates to faucets of the reciprocating plug, spring actuated type and has for its object to provide a faucet of this 15 type which will be simple and inexpensive in construction, will be self-closing and at the same time adapted to be held open if desired, will be easily taken apart for cleaning or replacement of worn parts, will not readily get out of order and will be effective 20 in operation.

With the above described objects, and other objects hereinafter explained in view my invention consists in the construction and combination of elements hereinafter 25 described and claimed.

Referring to the drawings;

Figure 1 is a central vertical longitudinal sectional view of a faucet embodying my invention, showing the faucet closed.

Figure 2 is a view similar to Figure 1 30 but showing the faucet open.

Figure 3 is a side view of a portion of the means for opening the faucet and holding it open, the parts being shown in the position which they assume when the faucet is 35 closed.

Figure 4 is a view similar to Figure 3 but showing the parts in the position which they assume when the faucet is to be held 40 open.

Figure 5 is an end view of the faucet.

Figures 6 and 7 are views showing the packing ring in vertical section and in end view respectively.

In the drawings 1 indicates the inner 45 member of the faucet casing consisting of a piece of straight tubing screwthreaded in its rear portion as shown at 2 to receive a nut 3 on the outside of the wall 4 of the tank from which liquid is to be drawn, and a nut 5 on the inside of the wall 4, these nuts bearing against gaskets 6 and 7 respectively, of rubber or other material adapted to be compressed to prevent leakage about the

tube 1 where it passes through the usual 55 faucet opening in the wall 4.

8 indicates the outer member of the faucet casing also formed of a straight piece of tubing, having an abutment 9 formed at its inner end adapted to fit over and be secured 60 on the forward end of the inner casing member 1. Near its rear end this outer casing member has formed in its under side a discharge opening 10, and it is internally 65 screwthreaded at its forward end as shown at 11.

12 indicates a cylindrical plug valve which fits within and is adapted to reciprocate in the outer casing member 8. This plug valve is carried by a valve rod 13 the inner end 70 of which is preferably connected by a ball and socket joint with the plug as shown. This valve rod extends through a central opening in a cap 14 which is externally 75 screwthreaded at its inner end to engage the screwthread 11 of the outer casing member 8, and carries on its outer end a double cam by means of which the plug valve is drawn outward when the valve rod is rotated as 80 hereinafter described.

The double cam consists of fixed cams 25 and 26 formed in a cylindrical shell extending forward from the head of the cap 14, the two cams being identical in shape but oppositely arranged with reference to the 85 axis of the cap, each extending from a point 27 near the head of the cap to a point 28 at a distance from the head of the cap corresponding to the distance through which the plug valve is to be moved. 90 The valve rod 13 is provided on opposite sides with radially extending lugs 30 and 31 the rear faces of which, that is the faces toward the cap 14, are flat and in a plane at right angles to the axis of the valve rod. At their outer points 28 the cams are cut off in a plane at right angles to the axis of the cap so as to form ledges 32 on which the lugs 30 and 31 carried by the 95 valve rod may rest and from which they will not tend to slip off. From the ends of these ledges 32 the shell in which the cams are formed is cut away on lines parallel with the axis of the cap to the points 27.

The plug 12 has formed in its outer end an annular recess 17 to receive the inner portion of an expansion coiled spring 18 the outer portion of which is received in the inner end 100 105

of the cap 14, the spring thus bearing at one end against the plug 12 and at the other end against the head of the cap 14 and acting to separate the plug and cap, forcing the cap inward against its seat.

On the valve seat formed by the inner end of the inner casing member 1 is arranged a packing ring 20 which may be of wood or any slightly compressible material, and is preferably carried by a ring 21 of metal which is L shaped in cross section having its inner diameter slightly less than the inner diameter of the inner casing member 1 so that, when in place, its inner edge forms a narrow ledge extending into the bore of the inner casing member. When it is desired to remove a packing ring all that is necessary, the cap 14 being unscrewed and removed with the plug 12, is to insert a rod of suitable diameter through the rear end of the inner casing member 1 and push the packing ring out through the outer casing member, or, by means of a suitably hooked instrument, to reach in through the outer casing member 25 and after engaging its hook with the ring 21, and draw it out with the ring 20.

The ball and socket connection of the valve rod 13 with the plug 12, as shown, is provided by forming centrally of the outer end of the plug a recess 35 adapted to receive the ball shaped head 36 formed on the inner end of the valve rod and forcing the walls of the recess, between it and the annular recess 17, inward to enclose the head.

The valve rod 13 is provided at its outer or forward end with a cross piece 37 by which it may be rotated.

When it is desired to open the faucet, the parts being in the position in which they are shown in Figure 1, with the lugs 30 and 31 resting at the points 27 and the spring 18 being in expanded position forcing the plug 12 against the packing ring 20 and closing the discharge opening 10, by rotating the valve rod 13 by means of the cross bar 37 the lugs 30 and 31 are caused to travel outward on the cams 25 and 26 drawing the plug 12 outward against the resistance of the spring 18 away from its seat and away from the dis-

charge opening 10, permitting liquid to flow freely. When the lugs 30 and 31 reach the ledges 32 the plug will be fully withdrawn. If it is desired to have the faucet remain open the lugs 30 and 31 will be allowed to rest on the ledges from which they will not readily slip off their under or rear faces being in a plane at right angles to the axis of the ledges which are also in a plane at right angles to the axis and the spring 18 acting to hold the lugs against the ledges. When it is desired to have the faucet close, the valve rod is rotated in either direction sufficiently to move the lugs off the ledges. If the valve rod is rotated to the right, the lugs will pass over the edges of the ledges and be drawn rearward at once to the points 27, the plug being forced rearward against its seat. If the valve rod is rotated in the opposite direction, the lugs will be drawn by the force of the spring downward along the cams 25 and 26 and return to the points 27.

Having thus described my invention what I claim is:

In a reciprocating plug faucet, the combination with an outer casing member having a valve seat at its rear end and a discharge opening in its side, of a plug valve fitting said outer casing member and adapted to reciprocate therein and to close the discharge opening, a cap secured on the outer end of said casing member, an expansion spring between the plug and the cap, a valve rod connected to the plug and extending through the cap, a pair of oppositely arranged forwardly extending cams carried on the outer end of the cap each having at the point farthest from the cap a ledge in a plane at right angles with the axis of the casing, and oppositely arranged radially extending lugs carried by the valve rod in position to bear against said cams, each of said lugs having its inner face flat and in a plane at right angles with the axis of the valve rod adapted to be held on said ledges by said expansion spring.

In testimony whereof I affix my signature this thirteenth day of June 1921.

HENRY G. CORDLEY.
